(57) **CLAIM**

The ornamental design for a storage box, as shown and described.

DESCRIPTION

FIG. 1 is a top perspective view of a storage box showing my new design according to a first embodiment;

FIG. 2 is a bottom perspective view of a storage box showing my new design according to the first embodiment;
FIG. 3 is a front view of FIG. 1;

FIG. 4 is a rear view of FIG. 1;

FIG. 5 is a left view of FIG. 1;

FIG. 6 is a right view of FIG. 1;

FIG. 7 is a top view of FIG. 1;

FIG. 8 is a bottom view of FIG. 1;

FIG. 9 is an enlarged view of the selected portion "9" in FIG. 1;

FIG. 10 is an enlarged view of the selected portion "10" in FIG. 2;

FIG. 11 is a top perspective view of a storage box showing my new design according to a second embodiment;

FIG. 12 is a bottom perspective view of a storage box showing my new design according to the second embodiment;

FIG. 13 is a front view of FIG. 11;

FIG. 14 is a rear view of FIG. 11;

FIG. 15 is a left view of FIG. 11;

FIG. 16 is a right view of FIG. 11;

FIG. 17 is a top view of FIG. 11;

FIG. 18 is a bottom view of FIG. 11;

FIG. 19 is an enlarged view of the selected portion "19" in FIG. 11;

FIG. 20 is an enlarged view of the selected portion "20" in FIG. 12;

FIG. 21 is a top perspective view of a storage box showing my new design according to a third embodiment;

FIG. 22 is a bottom perspective view of a storage box showing my new design according to the third embodiment;

FIG. 23 is a front view of FIG. 21;

FIG. 24 is a rear view of FIG. 21;

(Continued)

FIG. 25 is a left view of FIG. 21;
 FIG. 26 is a right view of FIG. 21;
 FIG. 27 is a top view of FIG. 21;
 FIG. 28 is a bottom view of FIG. 21;
 FIG. 29 is an enlarged view of the selected portion “29” in FIG. 21; and,
 FIG. 30 is an enlarged view of the selected portion “30” in FIG. 22.
 The dot-dash broken lines depict the boundaries of the enlargements that form no part of the claimed design.
